US00D885349S

(12) **United States Design Patent** (10) **Patent No.:** **US D885,349 S**
Brenk (45) **Date of Patent:** **** May 26, 2020**

(54) **ELECTRICAL DEVICE**

- (71) Applicant: **ABB Schweiz AG**, Baden (CH)
(72) Inventor: **Frank Brenk**, Hausach (DE)
(73) Assignee: **ABB SCHWEIZ AG**, Baden (CH)
(**) Term: **15 Years**
(21) Appl. No.: **29/603,310**
(22) Filed: **May 9, 2017**

Related U.S. Application Data

- (62) Division of application No. 35/500,806, filed on Oct. 9, 2015 (U.S. filing date under 35 U.S.C. 384), and having an international filing date of Oct. 9, 2015, now Pat. No. Des. 844,569.

Primary Examiner — Rhea Shields(74) *Attorney, Agent, or Firm* — Leydig, Voit & Mayer, Ltd.(57) **CLAIM**

The ornamental design for an electrical device, as shown and described.

DESCRIPTION

FIG. 1 is a top right front perspective view of the electrical device showing my new design;

FIG. 2 is a bottom plan view thereof;

FIG. 3 is a rear elevational view thereof;

FIG. 4 is a front elevational view thereof;

FIG. 5 is a left side elevational view thereof;

FIG. 6 is a right side elevational view thereof; and,

FIG. 7 is a top plan view thereof.

The broken lines in the drawings indicate portions which form no part of the claimed design.

1 Claim, 7 Drawing Sheets(56)
